UNITED STATES PATENT OFFICE.

MATTHIAS N. FORNEY, OF NEW YORK, N. Y.

RAILWAY SIGNALING APPARATUS.

SPECIFICATION forming part of Letters Patent No. 250,517, dated December 6, 1881.

Application filed July 11, 1881. (No model.)

To all whom it may concern:

Be it known that I, MATTHIAS N. FORNEY, of New York, county of New York, State of New York, have invented or discovered a new and useful Improvement in Railway Signaling Apparatus; and I do hereby declare the following to be a full, clear, concise, and exact description thereof, reference being had to the accompanying drawings, making a part of this specification, in which—like letters indicating like parts—

Figure 1, Sheet 1, is a plan view or diagram of a single-track railway-crossing, and of my improved apparatus as applied thereto. Fig. 15 2, Sheet 2, is a view in elevation of the home-signal apparatus, or the apparatus arranged at or near the crossing. Fig. 3 is a like view of one of the distant signals. Fig. 4, by an outline end view of a locomotive-cab, and frangible attachments thereon, and cross-section of track, illustrates one feature of invention, as presently to be described. Fig. 5 is a detached side view of one form of signal-shifting apparatus, suitable for the purposes in view. Fig. 6, 25 Sheet 3, is a horizontal sectional view, to an enlarged scale, of the shifting apparatus employed at the home signal, the section being taken in the plane of the lines $x' x'$, Fig. 7; and Fig. 7 is a vertical sectional view, approximately 30 through the middle of the apparatus, but showing some devices on opposite sides of the plane of section.

In a separate application I have described and claimed a system of interlocking disks or 35 sectors, by the use of which to lock one movable part or appliance of a railway structure by the movement of another.

The present application relates more particularly to a system of crossing-signals in which 40 the interlocking is effected by the use of disks or sectors, such as are referred to and claimed in said application.

In a crossing such as illustrated by the crossing tracks $T' T'$, it is important that there be 45 a home signal, A' , at the crossing, to indicate to an engineer approaching on either of the tracks from either direction whether the other is clear or not. Besides this, there should be distant signals $B', C', D',$ and E' in each direction, to indicate whether the line is clear or not, and they should be located far enough from the crossing, so that trains may be stopped

between them and the crossing. The distant signals it is proposed to work with wires in the usual way.

On Sheet 2 the home signal is represented at Fig. 2, and the distant signal at Fig. 3. The home signal consists of a double semaphore-arm, A^2 , attached to a vertical shaft, B, the whole being supported by a quadruped frame, 60 C^2 , resting on a bed-plate, D^2 .

The safety-signal may consist of a vertical board or plate, E^2 , (shown in dotted lines,) and placed at right angles to the danger-signal A^2 . Consequently, when the latter is at right angles to one line of track, and indicates "danger" or "stop" to an engineer approaching thereon, the safety or line-clear signal is displayed to the other. On top of the cab, or in any suitable position, socketed castings a are placed. 70 These carry what will be called "safety-staffs" b . Holes are drilled through the castings and the staffs, and they are secured by a string or wire and seals, $c c$.

On the ends of the home semaphore A^2 wooden arms $R R$ are attached. These are so arranged that in case an engine should pass this signal while displaying danger to the engineer, one of the arms $R R$ would break off the safety-staff b , and as the engineer could not 80 place and reseal another, the breaking of a staff would be a "tell-tale" which would show whether he had passed a signal at "danger."

The shaft B is turned by a worm-gear, Q, and crank T. The distant signals are operated by 85 sheaves S S and levers U U U. Wire ropes V V are wound on these sheaves and connected with the distant signals. In Sheet 3 these parts are shown on a larger scale.

The interlocking gear is of the same kind as 90 that used in connection with the switch as described in the application above referred to, the only important difference being that four pulleys or sheaves for the distant signals are used instead of one.

The shaft B has a circular disk, A, which engages with other disks, O C C C, attached to the sheaves S S S S. Each of the vertical disks has a slot or notch, c , in its edge. These notches in C C C C are so located that when the levers 100 U U are thrown so that the signals are at danger, the notches c are opposite to the disk A, as shown in the left side of Fig. 7. Consequently, when all the levers are shifted to indicate

"danger," A and the shaft B can revolve freely. The disk A has also a notch, e, Fig. 6, in its edge, which is located in such a position that when it comes opposite to any one of the disks 5 C C O C the home safety-signal is displayed to the track with the signal of which that disk is connected.

It will be seen that when the notch e comes opposite to a disk, C, the latter is free to revolve, and that all the others are locked by the periphery of the disk A entering the notches e in such other disks. As soon as a disk, C, is moved from a position indicating danger its full periphery enters the notch e, and so locks 15 the disk A, and consequently the home signal, and the latter is not unlocked until such disk C and the distant signal are again placed so as to indicate danger. It thus follows that no distant signal can be moved to indicate "line 20 clear" unless the home signal gives the same indication, and that no two distant signals can indicate "line clear" at the same time, and that the home signal can be moved only when all the distant signals are set at "danger," and also 25 that when any line is cleared the home and distant signals of the other line are locked at "danger."

T² T² are spring-treadles, which engage with the notches f f f f, to hold the sheaves and 30 levers in either of the two positions of "danger" or "line clear."

It sometimes happens with an arrangement of signals of this kind that after they are placed so as to indicate "line clear" to one 35 track the attendant will suddenly become confused or alarmed and will suddenly shift them after a train has passed the distant signal on one track, and thus admit a train on the other track. To guard against this the home signal 40 is arranged so as to be operated by a worm, Q', and a worm-gear wheel, Q Q, and a crank, T, Figs. 2 and 5. With this arrangement, if a signal-man should give the signals of "line clear" to one track and a train should pass the distant signal, and he should then become confused and endeavor to change the signals, he must first put the distant signal which was at "line clear" at "danger," and then before he can 45 put any other distant signal at "line clear" he must first move the home signal from one track to the other. To do this he must turn the crank a certain number of times, which would occupy a sufficient amount of time for the approaching train to pass if running fast, or be stopped by 50 the changing home signal if running slow. At any rate while he is engaged in moving the home signal no other trains can be admitted.

The distant signal shown in Fig. 3 consists of a post, F, to which a shaft, G, which carries the semaphore H and safety-signal I, is attached. On the lower end of the shaft are two pulleys, J and K. The former has a chain or wire rope wound on it, which passes over another pulley, L, and has a weight, M, attached to the other end. This is for the purpose of pulling the signal so as to indicate 65

"danger." The wire by which the signal is moved from the home signal to indicate "line clear" is attached to the lower pulley, K.

N is a wooden arm attached to the shaft 70 with an iron weight or anvil, O, on its outer end placed in a proper position to strike a torpedo attached to the side of the engine-cab by a suitable support, P. The object of this is to attract the attention of the engineer in case 75 he should inadvertently pass the signal when it is set at "danger." When the shaft is turned so as to bring the "line-clear" signal in view the arm N is turned with it, so as not to come in contact with the torpedo. 80

Modifications in the forms of the devices may be made, provided the combination and operation are substantially preserved—as, for example, any or all the disks may be flanged to a cup shape and the notches cut in the edges 85 of such flanges, so that, the edges of the flanges playing in the notches, or the notches coming into line, locking and unlocking may be done in the manner set forth. Such devices are included within the terms "disk" and "sector," 90 as herein used; but it should also be stated that a sector having the necessary length of arc may take the place of any of the vertical disks described.

The same apparatus may be used on a double-track crossing, and, with, say, three vertical disks and a proper spacing of the notches, 95 may be applied to a single or double track junction. In fact, the number of vertical disks may be varied from two upwardly, one for each 100 of two conflicting lines, as the exigencies of the case may require.

The frangible tell-tale and the detonating alarm herein described are not claimed herein, 105 but will form the subject-matter of a separate application.

It will be observed that in the construction shown and described the peripheries of the interlocking disks or sectors cross each other or are arranged in different planes, and in this, 110 among other respects, differ from the construction shown and described in English Patent No. 3,427 of 1869, which latter is hereby disclaimed.

I claim herein as my invention—

In a signaling apparatus for railway-crossings, a notched disk or sector on a rotary home-signal shaft, arranged in one plane of motion, in combination with two or more rotary notched signal-actuating disks or sectors, arranged with their notched peripheries crossing or intersecting in other planes the notched periphery of the first disk or sector, substantially as set forth, whereby when the home signal is set for any one line clear the distant signal for that line will be unlocked and the disks or sectors of all 120 conflicting signals will be locked.

In testimony whereof I have hereunto set my hand.

MATTHIAS N. FORNEY.
